US00D826974S

(12) **United States Design Patent** (10) **Patent No.:** **US D826,974 S**
(45) **Date of Patent:** **** Aug. 28, 2018**

(54) **DISPLAY SCREEN OR PORTION THEREOF
WITH GRAPHICAL USER INTERFACE**

(71) Applicant: **Nanolumens Acquisition, Inc.**,
Norcross, GA (US)

(72) Inventor: **Jorge Perez-Bravo**, Alpharetta, GA
(US)

(73) Assignee: **Nanolumens Acquisition, Inc.**,
Norcross, GA (US)

(**) Term: **15 Years**

(21) Appl. No.: **29/621,572**

(22) Filed: **Oct. 10, 2017**

Related U.S. Application Data

(63) Continuation-in-part of application No. 29/592,952,
filed on Feb. 3, 2017.

(57) **CLAIM**

The ornamental design for a display screen or portion thereof with graphical user interface, as shown and described.

DESCRIPTION

FIG. 1 is a front elevation view of a display screen or portion thereof with graphical user interface showing the new design;

FIG. 2 is a front elevation view of a second embodiment thereof; and,

FIG. 3 is a front elevation view of a third embodiment thereof.

The outermost broken lines illustrate a display screen or portion thereof and form no part of the claimed design. The remaining broken lines, illustrating portions of the graphical user interface, form no part of the claimed design.

1 Claim, 2 Drawing Sheets
